FIG. 5 is a left view thereof;
FIG. 6 is a top view thereof;
FIG. 7 is a bottom view thereof;
FIG. 8 is a perspective view of a charm or a pendant for inclusion in an earring, a necklace, a bracelet, a ring, an anklet, or another jewelry item;
FIG. 9 is a front view thereof;
FIG. 10 is a back view thereof;
FIG. 11 is a right view thereof;
FIG. 12 is a left view thereof;
FIG. 13 is a top view thereof;
FIG. 14 is a bottom view thereof;
FIG. 15 is a perspective view of a charm or a pendant for inclusion in an earring, a necklace, a bracelet, a ring, an anklet, or another jewelry item;
FIG. 16 is a front view thereof;
FIG. 17 is a back view thereof;
FIG. 18 is a right view thereof;
FIG. 19 is a left view thereof;
FIG. 20 is a top view thereof;
FIG. 21 is a bottom view thereof;
FIG. 22 is a perspective view of a charm or a pendant for inclusion in an earring, a necklace, a bracelet, a ring, an anklet, or another jewelry item;
FIG. 23 is a front view thereof;
FIG. 24 is a back view thereof;
FIG. 25 is a right view thereof;
FIG. 26 is a left view thereof;
FIG. 27 is a top view thereof;
FIG. 28 is a bottom view thereof;
FIG. 29 is a perspective view of a charm or a pendant for inclusion in an earring, a necklace, a bracelet, a ring, an anklet, or another jewelry item;
FIG. 30 is a front view thereof;
FIG. 31 is a back view thereof;
FIG. 32 is a right view thereof;
FIG. 33 is a left view thereof;
FIG. 34 is a top view thereof;
FIG. 35 is a bottom view thereof;

(Continued)

FIG. 36 is a perspective view of a charm or a pendant for inclusion in an earring, a necklace, a bracelet, a ring, an anklet, or another jewelry item;
FIG. 37 is a front view thereof;
FIG. 38 is a back view thereof;
FIG. 39 is a right view thereof;
FIG. 40 is a left view thereof;
FIG. 41 is a top view thereof;
FIG. 42 is a bottom view thereof;
FIG. 43 is a perspective view of a charm or a pendant for inclusion in an earring, a necklace, a bracelet, a ring, an anklet, or another jewelry item;
FIG. 44 is a front view thereof;
FIG. 45 is a back view thereof;
FIG. 46 is a right view thereof;
